UNITED STATES PATENT OFFICE.

WILLIAM TWEEDDALE AND JONATHAN MOORE, OF BROOKLYN, NEW YORK,
ASSIGNORS TO THE NORTH AMERICAN IRON WORKS, OF NEW YORK
CITY.

DESIGN FOR FOUNTAINS AND VASES.

Specification forming part of Design No. 7,513, dated June 30, 1874; application filed June 6, 1874.
[Term of patent 7 years.]

To all whom it may concern:

Be it known that we, WILLIAM TWEEDDALE and JONATHAN MOORE, of Brooklyn, in the county of Kings and State of New York, have invented a new and original Design for Fountains and Vases, of which the following is a specification:

The nature of our design for fountains and vases is fully represented in the accompanying print, to which reference is made.

The design consists of the spherical figure A on the top, having the ornamental figures B and lines C on its surface; also, the bead D at the top and the ornamental devices E and F on the sides of the cone which supports the top figure; also, the circular figures G and vertical plain spaces H, and figures-spaces I on the sides of the oval base of the cone; also, the ornamental border a of the base of the cone; also, the upper figure J, circular border K, side figures L, bottom figure L', and the dog's head M on the upper portion of the side of the column; also, the center figure N, plain oval border O, and the figures P at the sides of the border; also, the figure Q at the middle of the side of the column; also, the figure R at the bottom of the column; also, the spiral-figured band S on the sides and the figures T at the top of the corner columns U; also, the front and side ornamental figures V and W on the base of the corner column U; also, the ornamental cornice of the pedestal and top of the bowl X; also, the plain and lined vertical stripes b and d and the fluted figure e of the bowl; also, the top ornament f and the side ornament g of the basin-column; also, the figure h, border i, and head j on the side of the pedestal; and, also, the border k and the side ornamental figures l of the lower basin.

I also propose to apply these designs, except the spherical top ornament, to vases as well as to basin-columns.

We claim as our invention—

1. The design for a fountain, consisting of a spherical top, A, of the column, ornamented with the figures B and lines C, as set forth.
2. The design for a fountain or vase, consisting of the conical support of the top figure, ornamented by the bead D and figures E F, as set forth.

3. The design for a fountain or vase of the oval base, consisting of the cone, ornamented in the circular figures G and vertical plain stripes H and figured stripes I, as set forth.

4. The design for a fountain or vase, consisting of the ornamental border a of the base of the cone, substantially as specified.

5. The design for a fountain or vase, consisting of the figure J, border K, figures L L', and dog's head M, as set forth.

6. The design for a fountain or vase, consisting of the figure N, border O, and side figures P, as set forth.

7. The design for a fountain or vase, consisting of the ornamental figure Q, for the side of the column, as set forth.

8. The design for a fountain or vase, consisting of the ornamental figure R, for the side of the column.

9. The design for a fountain or vase, consisting of the spiral band S and top ornaments T of the corner columns U, substantially as specified.

10. The design for a fountain or vase, consisting of the front ornamental figure V and side ornaments W of the base of the corner column U, as set forth.

11. The design for a fountain or vase, consisting of the ornamental cornice X, for the pedestal and top of the bowl, as set forth.

12. The design for a fountain or vase, consisting of the plain stripes b, lined stripes d, and fluted figure e, for the bowl, as set forth.

13. The design for a fountain or vase, consisting of the top ornaments f and side ornaments g of the basin-column, as set forth.

14. The design for a fountain or vase, consisting of the ornamental figure h, borders i, and head j, for the inside of the pedestal, as set forth.

15. The design for a fountain or vase, consisting of the ornamental border k and the side ornaments l of the lower basin, as set forth.

WILLIAM TWEEDDALE.
JONATHAN MOORE.
